UNITED STATES PATENT OFFICE.

CHARLES R. KING AND ESTEL J. McCLELLAN, OF LOS ANGELES, CALIFORNIA.

GLOVE.

Application filed October 1, 1923. Serial No. 665,351.

To all whom it may concern:

Be it known that we, CHARLES R. KING and ESTEL J. McCLELLAN, citizens of the United States, residing at Los Angeles, in the county of Los Angeles and State of California, have invented certain new and useful Improvements in Gloves, of which the following is a specification.

It is the object of this invention to provide a glove, and more particularly a working glove, including a back, palm, and thumb piece; and in which the usual objectionable seam around the base of the thumb is eliminated; and in the construction of which the number of operations is reduced to a minimum, and an appreciable saving in thread is effected.

More particularly it is the object of the invention to provide a thumb piece for a glove having its base extended laterally at the side which is usually cut away, so as to provide a thumb piece having symmetrical sides, in order that the die for cutting said thumb pieces may be used for both right and left hand gloves without reversing the same; and so as to also provide a base for the thumb piece of a width adapting the same to extend from the center seam of the palm of the glove, all the way around to the side edge of the back of the glove, the palm of the glove being formed without the usual depending strip at its side edge beyond its thumb portion. By this arrangement it will be seen that the base of the thumb piece may be stitched directly to the back of the glove to form the side seam, thereby eliminating stitching of said base of the thumb piece to said usual depending strip of the palm piece, and then stitching the outer edge of said depending strip to the back of the glove in order to form the side seam, as is the practice in the constructions heretofore employed. As a consequence, the extra seam around the outside of the base of the thumb, and the extra operation and thread necessitated by the stitching of said seam, is eliminated.

The invention will be readily understood from the following description of the accompanying drawings, in which:

Fig. 1 is a plan view of the blanks for the back, palm, and thumb of the improved glove.

Fig. 2 is a plan view of the palm piece with the thumb stitched to the same.

Fig. 3 is a similar view showing the thumb

turned back to the position it assumes in the finished glove.

Fig. 4 is a plan view showing the back stitched to the palm and thumb pieces. 60

Fig. 5 is a perspective view of the finished glove.

The back and palm of the glove are preferably separate blanks, the back being shown at 1, and having straight sides 2 and fingers 3. The palm 4 is preferably cut in accordance with usual practice to form the index and little fingers as shown at 5, and is provided with a straight side 6 at the little finger and extending to the base of the palm, 70 and with a straight side 7 at the index finger which is inwardly offset at the lower portion of the palm so as to form an elongated cut-out portion 8 extending from the base of the palm to the base of the thumb. 75

A longitudinal medial slit 9 is formed in the palm and extends from the base thereof to the base of the thumb, thus providing a depending strip 10 in said palm which forms the inside of the thumb of the glove. 80 The edge of strip 10 is curved to conform to the contour of the thumb as shown at 11.

The upper end of slit 9 and the upper edge of the cut-out portion 8 are angularly disposed with relation to the sides of thumb strip 10, preferably by similarly curving said parts toward the side edge 7 of the palm as shown at 12.

The thumb piece for the glove comprises a thumb portion 14 adapted to form the outside of the thumb and conforming to the contour of the thumb strip 10, and a base 15 integral with said thumb portion and of a length adapted to extend from the base of the thumb to the lower edge of the glove, so as to form the portion of the palm directly below the thumb. 90

The sides of base 15 project laterally beyond the sides of thumb portion 14, so that oppositely inclined angularly disposed edges 100 16 connect the sides of said thumb portion and the sides of said base, said edges being preferably curved similarly to curved edges 12 of the palm of the glove.

The thumb piece is formed with symmetrical sides so that it may be used in making right or left hand gloves, thereby simplifying the operation of cutting the blanks for the thumb pieces, by eliminating the necessity for reversing the cutting die. 110

In assembling the glove as thus described,

the thumb piece is placed upon the palm piece as shown in Fig. 2, and the edges of the thumb portions 10 and 14, and the curved edges 12 and 16 are stitched together as shown at 17. The inner side edge of the base 15 is also stitched to the edge of the palm piece formed by slit 9, as shown at 18, and the thumb which is thus formed is then turned inside out as shown in Fig. 3, so that the thumb is in its natural position, with the base 15 extending below the same.

The laterally extended inner side edge of base 15 being thus fixed to the edge of the palm piece formed by slit 9, the outer side edge of base 15, which projects laterally the same distance, will extend across the cut-out portion 8 of the palm piece into alignment with the side edge 7 thereof, so as to fill in the palm of the glove.

20 The glove is finished by stitching edges 6 and 7 of the palm piece, and the outer side edge of base 15 of the thumb piece, to the edges 2 of the back 1 of the glove, as shown at 19, said stitching being continued around 25 the index and little fingers of the palm, and around the edges of separate finger inserts 20 for the two middle fingers of the glove. The wrist of the glove may be finished in any usual manner, as by binding the same as 30 shown at 21 in Fig. 5.

It will be noted that the lateral extension of the base of the thumb piece so that it may be stitched directly to the edge of back 1, without first stitching said base to an intermediate depending side strip of the palm and then stitching said palm strip to the edge of the back, as is the present practice, eliminates the objectionable seam around the outside of the base of the thumb of the 40 glove, and also saves the thread and labor incident to the formation of such an extra seam.

It will be apparent that various changes may be made in the construction, combination, and arrangement of parts as thus described, without departing from the spirit of the invention.

What is claimed is:

1. A glove comprising a back, a palm piece provided at its lower edge with a longitudinally extending medial slit inclined at its upper end toward one side edge of said palm piece, the lower portion of said side edge of the palm piece being cut away 55 with the upper edge of said cut-out portion inclined similarly to said inclined end of said medial slit, the portion of said palm piece between said slit and said cut-out portion forming a depending thumb portion 60 spaced from the side edge of said palm piece, and a thumb piece having a base projecting laterally at both side edges so as to form a symmetrical structure adapted for either right or left hand gloves, the edges of 65 said thumb piece between the side edges of

the thumb portion thereof and the side edges of its base being inclined in opposite directions on lines of curvature corresponding to said upper edge of said cut-out portion of the palm piece and said upper end 70 of the slit therein, said thumb piece having the edges of the thumb portion thereof and said oppositely inclined edges of the same fixed to the edge of said depending thumb portion of the palm piece to form a thumb 75 for the glove adapted to be turned back upon the palm thereof with the base of the thumb piece positioned at the side edge of said palm below said thumb, said base extending laterally at its inner side edge to 80 the edge of said palm piece at said slit and extending laterally at its outer side edge across said cut-out portion of the palm to the edge of the back of the glove and being stitched thereto, whereby a seam around the 85 base of the thumb and spaced from the edge of the back of the glove is eliminated.

2. A glove comprising a back, a palm piece provided at its lower edge with a longitudinally extending medial slit, the lower portion of one side edge of the palm piece being cut away with the upper end of said cut-out portion inclined upwardly and outwardly, the portion of said palm piece between said slit and said cut-out portion 95 forming a depending thumb portion spaced from the side edge of said palm piece, and a thumb piece having a base provided with a laterally projecting outer side edge, the edge of said thumb piece between a side edge 100 of the thumb portion and said outer side edge of its base being inclined similarly to said upper end of said cut-out portion of the palm piece, said thumb piece having its side edges between its thumb portion and its 105 base and the side edges of said thumb portion fixed to the edge of said depending portion of the palm piece to form a thumb for the glove adapted to be turned back upon the palm thereof with the base of the thumb 110 piece positioned at the side edge of said palm below said thumb, said base extending laterally at its outer side edge across said cut-out portion of the palm to the edge of the back of the glove and being fixed 115 thereto.

3. A glove comprising a back, a palm piece provided at its lower edge with a longitudinally extending medial slit inclined at its upper end toward one side edge of said palm piece, the lower portion of said side edge of the palm piece being cut away with the upper end of said cut-out portion inclined similarly to said inclined end of said medial slit, the portion of said palm 120 piece between said slit and said cut-out portion forming a depending thumb portion 125 spaced from the side edge of said palm piece, and a thumb piece having a base provided with a laterally projecting outer side edge, 130

the edges of said thumb piece between the side edges of the thumb portion thereof and the side edges of its base being inclined in opposite directions on lines of curvature corresponding to said upper end of said cut-out portion of the palm piece and said upper end of said medial slit, said thumb piece having its side edges between its thumb portion and its base and the side edges of said thumb portion fixed to the edge of said depending portion of the palm piece to form a thumb for the glove adapted to be turned back upon the palm thereof with the base of the thumb piece positioned at the side edge of said palm below said thumb, said base extending laterally at its outer side edge across said cut-out portion of the palm to the edge of the back of the glove and being fixed thereto.

4. A glove comprising a back, a palm piece forming a depending thumb portion laterally spaced at its outer side edge from the prolongation of the side edge of the palm piece proper, the upper ends of the side edges of said thumb portion being inclined upwardly and outwardly, and a thumb piece having a base, the edges of said thumb piece between the side edges of the thumb portion thereof and the side edges of its base being inclined in opposite directions on lines of curvature corresponding to said upper ends of said side edges of the depending thumb portion of the palm piece, said thumb piece having its side edges between its thumb portion and its base and the side edges of said thumb portion fixed to the edges of said depending portion of the palm piece to form a thumb for the glove adapted to be turned back upon the palm thereof, with the base of the thumb piece forming the palm below said thumb and said base of the thumb piece extending laterally at its outer side edge to the edge of the back of the glove and being fixed thereto.

5. A glove comprising a back, a palm piece forming a depending thumb portion laterally spaced at its outer side edge from the prolongation of the side edge of the palm piece proper, the upper end of the outer side edge of said thumb portion being inclined upwardly and outwardly, and a thumb piece having a base, the edge of said thumb piece between the outer side edge of the thumb portion thereof and the outer side edge of its base being inclined similarly to said upper end of said outer side edge of the depending thumb portion of the palm

piece, said thumb piece having its side edges between its thumb portion and its base and the side edges of said thumb portion fixed to the edges of said depending portion of the palm piece to form a thumb for the glove adapted to be turned back upon the palm thereof, with the base of the thumb piece positioned at the side of said palm below said thumb and said base of the thumb piece extending laterally at its outer side edge to the edge of the back of the glove and being fixed thereto.

6. A glove comprising a back, a palm piece having a longitudinally extending cut-out portion at one side edge thereof forming a portion of said palm piece spaced from the side edge of the palm and adapted to be turned back upon the palm proper to form the front of the thumb of the glove, the outer side edge of the front of the thumb curving into the side edge of the palm proper at the base of the thumb so as to follow the contour of the edge of the hand between the thumb and index finger, and a thumb piece fixed to the edge of said front of the thumb to form the back of the same and having a depending base forming the portion of the palm of the glove below said thumb and extending laterally at its outer side edge across the cut-out portion of the palm piece to the edge of the back of the glove and being stitched thereto.

7. A glove comprising a back, a palm piece forming a depending thumb portion laterally spaced at its outer side edge from the prolongation of the side edge of the palm piece proper, and a thumb piece provided with a base having equi-distantly, laterally projecting, symmetrical sides whereby said thumb piece is adapted for either right or left hand gloves, said thumb piece having its side edges between its thumb portion and its base and the side edges of said thumb portion fixed to the edges of said depending thumb portion of the palm piece to form a thumb for the glove adapted to be turned back upon the palm thereof, with the base of the thumb piece forming the palm below said thumb and said base of the thumb piece extending laterally at its outer side edge to the edge of the back of the glove and being fixed thereto.

In testimony whereof we have affixed our signatures to this specification.

CHARLES R. KING.
